UNITED STATES PATENT OFFICE.

HENRY FREUND, OF WAUKEGAN, ILLINOIS.

AUTOMATIC WINDOW-SCREEN.

1,257,074.

Specification of Letters Patent. Patented Feb. 19, 1918.

Application filed August 29, 1916. Serial No. 117,514.

To all whom it may concern:

Be it known that I, HENRY FREUND, a citizen of the United States, residing at Waukegan, in the county of Lake and State 5 of Illinois, have invented certain new and useful Improvements in Automatic Window-Screens, of which the following is a specification.

This invention relates to an improvement 10 in window screens, and more particularly to a screen which is so constructed that it may be attached to a window sash in such a manner that as the sash is opened the screen will be automatically carried to a 15 position to fit over the opening, means being provided to take up the screen as the window is again brought to the closed position.

An object of my invention is to provide 20 a screen of the type above described which is so constructed that it may be fitted to windows as installed in a completed building or may be set in place during the construction of the building, and which presents the screen structure in such relation 25 that the outer edge thereof may be detachably connected with the window sash in a relation to be raised and brought over the opening as the window may be opened or 30 to remain in its normal relation irrespective of the movement of the window, when the attaching means is not fitted in place.

A further object is to provide means to 35 guide the screen in the proper path of movement at its edges while at the same time absolutely precluding the possibility of open spaces being left at the edges through which insects might pass; and to provide means which will take up the screen as the window 40 may be again closed and will act to hold the screen taut and properly stretched when the same is attached to the window sash to be drawn in place over the opening left by movement of the same.

With the above and other objects in view, 45 my invention consists in certain novel features of construction and combinations of parts which will be hereinafter set forth in connection with the drawings and then 50 more particularly pointed out in the claims.

In the drawings:

Figure 1 is a view in elevation of a window showing my invention fitted in place thereon.

Fig. 2 is a view in section through the lower rail of a window sash and through

the parts of my invention as mounted on the inside window sill.

Fig. 3 is a view in elevation of the roller case. 60

Fig. 4 is a longitudinal vertical sectional view through the structure shown in Fig. 3.

Fig. 5 is a detail view showing the bearing brackets as mounted in the roller case at one end thereof. 65

Fig. 6 is a view similar to Fig. 5 showing the bearing bracket as mounted in the opposite end of the case.

Fig. 7 is an elevational view showing the guide member for the edge of the screen. 70

Fig. 8 is a detail view showing one form of sash lift with which my invention is particularly adaptable.

In the present disclosure I have illustrated the device as being fitted in place on 75 the inside sill of a window, and the case 1 is shaped so that it rises to have the greatest height adjacent to the inner edge of the sill and is then brought down in a gradual slope as indicated at 2 so that at the outer 80 edge of the sill adjacent to the sash rail 3, the case is comparatively low, thus permitting access to be had freely to the sash lift 4. From the above it will be seen that a structure is provided which is adapted to 85 be applied to a window as already installed in a completed building and at the same time does not in any way interfere with opening and closing of the window.

This case 1 is preferably made of sheet 90 metal, although it might be of wood or other suitable material, and is of a length that it fits between the sash of the casing portion of the window. The inclined wall 2 of the case is stopped short of the extreme forward 95 end of the case and the bottom 5, which is preferably constructed to be detachable from the main portion of the case is also shaped so that an opening is provided throughout the entire length of the case 100 as indicated at 6, in Fig. 3.

The metal guide plates 7 and 8 are fitted on the sash strips 9 and 10 at the opposite sides of the window, and as is better shown in Fig. 7, these guide plates have the outstanding flange portions 11 and 12 thereon which form the guide way 13 therebetween to receive the edge of the screen, the guide members 7 and 8 being so mounted that as a length of screen may pass out through the 110 opening 6 of the case, it may rise up in a vertical frame and be guided in the slot 13.

In fitting the case 1 in place, the sash strips 9 and 10 will be mitered at their lower ends as shown in Fig. 2, and then the case will be fitted in place with the lugs 14 of the 5 guide plates 7 and 8 engaged in the slotted openings 15 of the case to hold the same against backward movement to be displaced from the proper position, it of course being understood that the ends of the sash strips 10 9 and 10 will have bearing against the case to prevent displacement of the same through upward movement.

The bearing members 16 and 17 are mounted within and secured on the end of 15 the case 1, and these bearing members are provided with the bearing openings 18 which are disposed adjacent to the opening 6 from the case so that the idler roll 19 may be fitted therein and will be adjacent to the 20 opening. The bearing member 16 has a squared socket 20 formed at a point spaced from the bearing opening 18, and bearing member 17 has a bearing opening 21 provided in corresponding location, these bearing 25 and socket openings being provided to receive the pintle end 22 and the squared end 23 of the take up roller 24. This take up roller 24 is constructed somewhat after the manner of the usual spring shade roller 30 and the spring mandrel 25 has the spring 26 mounted therearound to normally exert force to turn the roller 24 in one direction, it being understood that the pawl or ratchet or other holding means is not provided to 35 lock the roller against turning under the impulse of the spring.

A screen strip 27, which may be of wire mesh fabric or other suitable screen material, is connected at one end on the roller 40 24 and has the free end led under the idler roll 19 and out through the slotted opening 6 of the case, where it is connected with the binding strip 28 to be rigidly secured in connection therewith throughout its entire 45 width.

The sash lifts 4, one of which is shown in detail in Fig. 8, are preferably made of 50 pressed sheet, or cast metal and are provided with the key hole shaped openings 29 which will be left free and unobstructed even when the lifts are secured on the rail 3 of the sash. Hooks 30 and 31 are mounted on the binding strips 28 and are provided with enlarged 55 heads as indicated at 32, so that as these hooks may be fitted with the heads through the enlarged ends of the key hole shaped slots of the sash lifts 4 and are then drawn down to the reduced end of these slots 29, the hooks will be held against displacement. 60 It is preferable that these hooks 30 and 31 be mounted on the binding strip 28 to be capable of swinging movement and notches 65 33 and 34 are provided adjacent to the mounting of the hooks in the upper edge of the binding strip 28, so that as the hooks

may be swung down they will rest within the notches and will thus be substantially in line with the upper edge of this binding strip 28. By this arrangement of the hooks, they may be either inserted in the keyhole 70 shaped slots 29 of the sash lift and will in this relation cause the screen strip 27 to be unwound from the take up roller 24, or when the screen is not to be used, as in the case that the window is to be washed, the 75 hooks 30 and 31 may be released from the interfitted mounting in conjunction with the sash lifts and upon being turned down to rest in the notches 33 and 34 will be embodied in the main lines of the binding 80 strips 28, in this way being so placed that they will not catch in the clothing or upon the cloths which may be used to clean the window. It will be understood that the spring 26 is constantly exerting turning 85 force against the take up roller 24 in a direction to wind the screen strip 27 thereonto, and consequently the screen strips will be held taut and stretched at all times irrespective of the height to which the sash 90 may be raised, however, where a window sash is delicately balanced, this drawing force exerted upon the screen strip 27 may be sufficient to overcome the counterbalance of the weights and may exert a tendency to 95 draw the sash down, under which circumstances it will of course be understood that the sash might be worked up or that the window might have a lock of the eccentric type mounted on the sash strip to bear 100 against the sash and to hold the same against return movement to the closed position under the action of the spring 26.

While in the above description and in the drawings I have illustrated the device of 105 my invention as being applied on the upper side of an inside window sill, it will of course be apparent that where a new window is being installed or where a building is under construction, the case 1 might be 110 built in below the inside sill and under these circumstances, the sash strips 9 and 10 will be continuous as in the usual window construction and also the guide members 7 and 8 will be brought down to have their lower 115 ends bear against the upper side of the inside sill, and also it will be apparent that changes and modifications might be resorted to in the form and arrangement of the various parts of the structure as hereinbefore 120 set forth either in the use of the same in the building construction, or in the use as is herein disclosed, in view of which fact I do not wish to be limited to the exact disclosure, but rather only to such points as may be 125 limited by the claims.

I claim:

1. A window screen comprising a screen strip adapted to be connected detachably at one of its ends to a sliding sash, a case con- 130

structed to be mounted on a fixed part of the window casing and having means therein to take up and let out the screen strip as the sliding sash is moved so that this 5 screen strip will be carried over the opening left by the sash, and guide strips connected on opposite sides of the window casing to receive and guide the side edges of the screen strip and also provided with extension portions to engage with and secure the 10 casing detachably in such a position that the screen strip travels freely within the guide strips.

2. An automatic window screen comprising with a screen strip, a binding strip mounted on one end of said screen strip, means by which the binding strip is detachably connected with a sliding window sash, a case constructed to be mounted on the 20 window casing at that point adjacent which the edge of the sliding sash having the binding strip mounted thereon closes, a take up roller mounted within the case and having the free end of the screen strip connected therewith in a relation that as the sash is moved the roller will automatically reel up and unreel the strip, said case having openings therein and guide means to be mounted on the window casing to receive and 25 guide the side edges of the screen strip and provided with extensions to be received in the openings of the casing to secure the same detachably in the proper position for use.

3. An automatic window screen comprising a screen strip, a binding strip mounted on one end of said screen strip, means carried by the binding strip by which attachment can be removably made to a sliding sash, a case constructed to be mounted upon 35 the window casing at that point adjacent which the edge of the sliding sash having the binding strip secured thereto closes, a take up roller mounted within the case and

having the free end of the screen strip connected therewith in a relation that as the 40 sash is moved the roller will automatically reel up and unreel the strip, an idler roll carried in the case and over which the screen strip passes, said case having openings through the top thereof at the ends, and 50 guide strips connected with the window casing to receive the edges of the screen strip and having extensions to fit within the openings of the casing to retain the same detachably fitted in the position for use. 55

4. An automatic window screen comprising a screen strip having a binding strip on one end thereof, hooks connected on said binding strips, sash lifts mounted on a sliding sash and provided with openings to receive and hold said hooks to mount the screen strips in conjunction with the sash, a case constructed to be mounted on the inside sill of the window, an idler roll mounted in the case over which the screen strip is 60 drawn, a take up roller mounted within the case and having the free end of the screen strip connected therewith, a spring mounted in conjunction with the take up roller to normally exert turning force thereagainst 65 to cause the rollers to turn in a direction to wind the screen strip thereonto, said binding strip shaped to provide an insect stop between the screen strip and the sash, and 70 guide strips connected on opposite sides of the window casing to receive and guide the side edges of the screen strip while at the same time presenting portions arranged to 75 secure the case against displacement.

In testimony whereof I affix my signature 80 in presence of two witnesses.

HENRY FREUND.
